UNITED STATES PATENT OFFICE

162,858

NAIL POLISH BOTTLE HOLDER

Arthur E. McGlinchey, New York, N. Y., assignor to Gordon B. Taylor, Kearney, N. J., and Charles H. Boenig, Johnson, Vt.

Application May 7, 1949, Serial No. 2,522

Term of patent 3½ years

(Cl. D86—10)

To all whom it may concern:

Be it known that I, Arthur E. McGlinchey, a citizen of the United States of America and a resident of the city of New York, Borough of Brooklyn, in the county of Kings and State of New York, have invented a new, original, and ornamental Design for a Nail Polish Bottle Holder, of which the following is a specification, reference being had to the accompanying drawing, forming a part thereof.

The single figure is a perspective view of a nail polish bottle holder, showing my new design.

I claim:

The ornamental design for a nail polish bottle holder, substantially as shown.

ARTHUR E. McGLINCHEY.
